UNITED STATES PATENT OFFICE.

JAFEW S. VAN BUREN, OF ALBANY, NEW YORK.

DESIGN FOR A BRICK-REST.

SPECIFICATION forming part of Design No. 33,835, dated January 1, 1901.

Application filed December 3, 1900. Serial No. 38,567. Term of patent 14 years.

To all whom it may concern:

Be it known that I, JAFEW S. VAN BUREN, a citizen of the United States, residing at Albany, in the county of Albany and State of New York, have invented and produced a new and original Design for a Brick-Rest; and I do hereby declare the following to be a full, clear, and exact description of the same, reference being had to the accompanying drawing, forming a part thereof.

My invention is a new and useful design for a brick rest or support; and it consists in the novel features hereinafter described, reference being had to the accompanying drawing, which illustrates my design in perspective.

My design for a brick-rest consists in the novel form or configuration—to wit, a long flat bar A, having one of its lateral edges provided with two upwardly curved or arched

portions extending from points adjacent to the opposite ends of the bar and connected adjacent to the center of the bar.

In the drawing, A represents the flat bar, and B B represent the arched portions, extending along one lateral edge of the bar from points adjacent to the opposite ends of the bar and connected adjacent to the center of the bar.

What I claim, and desire to secure by Letters Patent, is—

The design for a brick-rest substantially as herein shown and described.

In testimony whereof I affix my signature in presence of two witnesses.

JAFEW S. VAN BUREN.

Witnesses:

E. R. HOBBS,
H. S. NELSON.
